UNITED STATES PATENT OFFICE.

FREDERICK CRUTCHLEY, OF BIRMINGHAM, ENGLAND, ASSIGNOR TO
CHARLES PRYSE, OF SAME PLACE.

SAFETY-LOCK FOR FIRE-ARMS.

SPECIFICATION forming part of Letters Patent No. 231,542, dated August 24, 1880.

Application filed March 26, 1880. (No model.) Patented in England September 15, 1879.

To all whom it may concern:

Be it known that I, FREDERICK CRUTCHLEY, of Birmingham, in the county of Warwick, England, have invented certain Improvements 5 in the Lock Mechanism of Double-Chambered Breech-Loading Guns, which improvements are fully set forth in the following specification and accompanying drawings—that is to say:

10 My invention has for its object improvements in the lock mechanism of double-chambered breech-loading guns whose hammers are internally placed, or what are known as "hammerless" guns; and it consists in the combinations of parts set forth in the annexed claims.

According to my invention, I use a double or forked mainspring acting directly upon the internal hammers, as shown clearly in the three side elevations, Figures 1, 5, and 10, where the 15 points *a'* of the spring *a* are clearly shown bearing against the shoulder *b'*, which is formed in each of the hammers *b*. These hammers *b* are hung upon the pivots *e* of the trigger-plate *c*. The under lever, *F*, for cocking and 20 for withdrawing the bolt *g* to open the gun, is also hung in a slot in and under the trigger-plate *c*, to work freely between the two internal hammers, which are impelled forward, when the triggers are pulled, by the forked 25 ends of my double mainspring.

All the views are shown with the gun mechanism in the cocked position, but locked by the safety-catch *h*, which bears upon the trigger *i*, preventing it from being lifted.

30 The safety-catch is unlocked by simply pushing the bolt *h* forward toward the front of the gun by means of the thumb-piece *h'*. After the gun is fired the breech is opened by means of the before-mentioned lever *F* being pressed 35 downward, which brings the pin *j* into the recess *k* of the hammers, which does not extend entirely across their faces, but leaves a web in each hammer, for the purpose of imparting greater strength to them. This will be more 40 clearly seen in the side elevation, Fig. 2, where the left leg of the mainspring and the left hammer are removed for greater clearness in illustrating the recesses *k* in the hammers. The 45 action of opening the breech also cocks the hammers, and they carry the safety-catch back 50 into the locked position, as shown, the ham-

mers themselves returning and settling under the sears *l*, but sufficiently forward to leave the necessary space, *m*, for allowing the safety-catch to be brought sufficiently forward to miss 55 the projections upon the trigger-plates.

Fig. 3 is a plan of the actions shown in elevation by Figs. 1 and 2, and Fig. 4 is a back-end elevation of the same action. Fig. 5 is a side elevation of a similar action, shown as 60 applied to a gun having a top lever, *N*, for opening the breech. In this case the hammers are carried to the cocked position by the two friction-rollers *o o* of the barrel-locking bolt *p*, (or the roller may be dispensed with.) The 65 safety-catch is moved forward to its locked position over the triggers by the horn *q*, which projects from the said barrel-locking bolt between the rollers, the safety-catch *h* being carried down in this case to meet the said horn *q*. 70

The inverted plan, Fig. 6, shows the top lever, *N*, turned to the right side of the gun and the barrel-locking bolt brought forward by the eccentric *r*, which projects from the shaft of the lever *N*. This plan also shows 75 the safety-catch *h* brought back by the before-mentioned horn *q*.

Fig. 7 is a plan showing the position of the top lever, *N*, when the gun is closed.

In some cases, where I wish to obtain a little 80 more leverage in bringing the hammer back to the cocked position, I crank the safety-bolt, as is illustrated by Fig. 8 in both side elevation and plan.

When the gun is fired the forked mainspring 85 propels the hammers forward in just the same manner as explained in the case of the gun having an under lever.

Fig. 10 also illustrates a top-lever action in side elevation, and the same action is represented in plan by Fig. 11. Here also the top lever, *N*, opens the breech by moving the barrel-locking bolt *p* backward; but in this case the end of the barrel-locking bolt carries only one roller, *s*, which works against the ruling-lever *t*, whose upper end bears against the projections *u* on the inner side of each of the hammers and forces them back into the cocked position. The extreme top end of this ruling-lever *t* also carries the safety-catch into its 90 locked position over the triggers. 95

Fig. 9 represents a top plan and also an in-

verted plan, showing the safety-catch arranged so as to indicate the two barrels separately and together—*i. e.*, I can move forward the catch *y*, allowing the right-hand barrel to be fired without unlocking the safety-catch *z*, which secures the left-hand barrel against being discharged. It would also be indicated which barrel was still loaded, and thus prevent many accidents in the use of the gun in the field.

10 The discharged barrel could also be reloaded without in any way interfering with the locked position of the barrel remaining loaded.

15 Figs. 12, 13, and 14 illustrate my forked mainspring V split edgewise, so as to form two supplementary light legs or wings, *w*, for the sears, which enables me to do without the sear-spring *x*, (shown in plan, Fig. 3,) thus considerably steadyng and simplifying the action by reducing the number of parts, be-
20 sides lessening the liability of any of the parts moving out of their positions. The double locking-catch is also illustrated as applied to this action, thus forming a combination at once simple, effective, and most secure against
25 accident of any kind.

Having now described several ways of applying my hereinbefore-described invention in practice both to top and bottom lever guns, I

would have it clearly understood that I do not confine myself to the exact details herein set forth; but

I do claim—

1. The combination, substantially as set forth, of the lever for opening the breech, the hammer, and sear with the safety-catch *h*, 35 sliding longitudinally in the top strap, and so combined with the hammer that it is thereby retracted as the breech is opened and locks the sear, as described.

2. The combination, substantially as set forth, in a double so-called "hammerless" gun, of the hammers, a four-leaf mainspring, the sear, and the breech-opening lever with a pair of safety-catches, *h*, sliding longitudinally in the top strap and retracted by the hammers 45 as the breech is opened, each catch being independently movable to release its hammer, as described.

In testimony that I claim the foregoing as my own I affix my signature in the presence 50 of two witnesses.

FREDERICK CRUTCHLEY.
